US00D477250S

(12) **United States Design Patent** (10) Patent No.: **US D477,250 S**
Leutz et al. (45) Date of Patent: ** Jul. 15, 2003

(54) **SURFACE CONFIGURATION OF A VEHICLE, TOY AND/OR OTHER REPLICAS**

Primary Examiner—Melody N. Brown

(74) Attorney, Agent, or Firm—Crowell & Moring LLP

(75) Inventors: **Volker Leutz**, Neckartailfingen (DE);
Conrad Hummel, Stuttgart (DE);
Andreas Kurbos, Leonberg (DE)

(57)

CLAIM

The ornamental design for a surface configuration of a vehicle, toy and/or other replicas, as shown and described.

(73) Assignee: **Smart GmbH**, Boeblingen (DE)

DESCRIPTION

(**) Term: **14 Years**

(21) Appl. No.: **29/168,534**

(22) Filed: **Oct. 4, 2002**

(30) **Foreign Application Priority Data**

Jul. 19, 2002 (DE) 402 05 951

(51) LOC (7) Cl. **12-08**

(52) U.S. Cl. **D12/91**

(58) Field of Search D12/86, 90-92;
D21/433, 435, 539, 549; 296/185

FIG. 1 is a front view of a surface configuration of a vehicle, toy and/or other replicas according to our novel design; FIG. 2 is a left, front perspective view of the surface configuration of a vehicle, toy and/or other replicas according to our novel design, the right, front perspective view being mirror symmetrical;

FIG. 3 is a left side view of the surface configuration of a vehicle, toy and/or other replicas according to our novel design;

FIG. 4 is a right side view of the surface configuration of a vehicle, toy and/or other replicas according to our novel design;

FIG. 5 is a right, rear perspective view of the surface configuration of a vehicle, toy and/or other replicas according to our novel design, the left, rear perspective view being mirror symmetrical;

FIG. 6 is a rear view of the surface configuration of a vehicle, toy and/or other replicas according to our novel design; and,

FIG. 7 is a top view of the surface configuration of a vehicle, toy and/or other replicas according to our novel design.

The broken lines included depict environment and are not part of the claimed design.
